GAS MASK CANNISTER

Robert K. Dyer, 1513 First National Building,
Oklahoma City, Okla.

Filed Jan. 25, 1965, Ser. No. 83,566

Term of patent 14 years

(Cl. D83—1)

FIG. 1

FIG. 2

FIG. 3

FIG. 4

FIG. 1 is a perspective view of the gas mask cannister looking at the front, top and one end of the cannister.

FIG. 2 is an elevational view showing the back of the cannister.

FIG. 3 is an elevational view showing the end of the cannister opposite to the end shown in FIG. 1.

FIG. 4 is a bottom view of the cannister.

I claim:

The ornamental design for a gas mask cannister as shown.
